UNITED STATES PATENT OFFICE.

JOHN THOMAS COLLINS, OF KOKOMO, INDIANA.

HEATING SYSTEM.

1,231,850.

Specification of Letters Patent.

Patented July 3, 1917.

Application filed May 8, 1916. Serial No. 96,177.

To all whom it may concern:

Be it known that I, JOHN THOMAS COLLINS, a citizen of the United States, residing at Kokomo, in the county of Howard and State 5 of Indiana, have invented certain new and useful Improvements in Heating Systems; and I do declare the following to be a full, clear, and exact description of the invention, such as will enable others skilled in the art 10 to which it appertains to make and use the same.

My invention relates to the type of furnaces which discharge heat into a room from a central heat discharge pipe and take fresh 15 air into the space within the shell of the furnace through a cool air jacket which surrounds said pipe. The principal object is to provide an improved means for forming the jacket in a simple and inexpensive manner and at the same time to provide means 20 for reinforcing the sheet metal top of the furnace shell to prevent warping thereof which would otherwise distort the grating usually disposed over the upper ends of the 25 heat discharge pipe and the cool air jacket.

With this general object in view, the invention resides in certain novel features of construction and in unique combinations of parts to be hereinafter fully described and 30 claimed, the descriptive matter being supplemented by the accompanying drawings which constitute a part of this application and in which:

Figure 1 is a vertical section of the improved furnace showing its application to a heating system in accordance with my invention;

Fig. 2 is a vertical section taken at right angles to Fig. 1 as indicated by the line 2—2 40 of Fig. 1;

Fig. 3 is a horizontal sectional view taken on the plane indicated by the line 3—3 of Figs. 1 and 2;

Fig. 4 is a perspective view of the upper 45 heat radiating ring of the furnace; and

Fig. 5 is a similar view of the lower ring.

In specifically describing the construction shown in the drawings above briefly referred to, similar characters indicate corresponding parts throughout the several views. The 50 numeral 1 designates a furnace proper which may be of any suitable construction provided with a dome-shaped upper end 2 having diametrically opposed smoke outlet openings 3. A lower heat radiating ring 4 surrounds and is spaced from the dome-shaped

upper end of the furnace, said ring being hollow and having projecting radially inward from its inner side a pair of smoke passages in the form of rectangular necks 5 having inclined inner ends 6 which rest on the sides of the dome-shaped upper end of the furnace, said necks registering with the openings 3 as shown most clearly in Fig. 2 and preferably having laterally extending 65 flanges or the like 7 by means of which they are secured to the furnace.

An upper radiating ring 8 of hollow formation is spaced above the ring 4, said upper ring having a pair of depending smoke passages 9 which telescope with similar passages 10 rising from diametrically opposite points on the ring 4, one of said passages 9 having a damper 10° which may be opened when building a fire in the furnace 1, it being 70 however normally closed, (see Fig. 2). Both the upper and lower rings are provided with clean-out passages 11 closed normally by doors 12, and the upper ring 8 is equipped with a smoke discharge neck 13, which latter 75 communicates with the smoke pipe 14 leading to a flue 15.

A cylindrical heat trapping shell 16 surrounds and is spaced from the furnace proper and both of the heat radiating rings 85 above described, the clean-out passages 11 of said rings and the smoke discharge neck 13 opening through said shell as clearly shown in Fig. 2. Dead air spaces for insulating purposes are eliminated in the improved 90 furnace and in lieu thereof the shell 16 is lined with asbestos as shown at 17 and a corrugated lining 18 of bright tin is secured in contact with the inner surface of the lining 17. The upper end of the shell 16 is 95 preferably reduced gradually in diameter into a somewhat frusto-cone shape, and said upper end is provided with a top 20 having a single opening 21 from which a hot air discharge pipe 22 rises.

A polysided wall 23 surrounds and is spaced from the pipe 22, forming therewith a cool air jacket, said jacket having its lower end closed by the top 20, this being preferably done by forming laterally extending 105 flanges on the lower edges of the wall 23 and by bolting or riveting said flanges to the top 20 as indicated at 24. A grating 25 extends over the upper ends of the pipe 22 and the wall 23, said grating allowing hot air 110 to be discharged from said pipe while permitting cool air to enter the aforesaid jacket

from which it is led through a pair of pipes 26 into a main upright passage 27, the lower end of said passage delivering into a shoe 28 which is in communication with the space 5 within the lower end of the shell 16.

In order to prevent the hot air within the shell 16 and pipe 22 from heating the cooler air within the jacket 23, the aforesaid pipe is preferably wrapped with asbestos as indicated at 29 and the top 20 is provided with a sheet of asbestos 30 which extends between the pipe 22 and the jacket 23, said sheet being preferably secured in place by the same means which anchors the aforesaid jacket 15 to the top 20.

A second cool air passage 31 discharges into the space within the lower end of the shell 16 (see Figs. 1 and 3), said passage having at its upper end a grating or the like 32, while a fresh air inlet 33 leads into either the passage 27 or that indicated at 31, preferably the latter. The inlet 33 is adapted to extend from the open air and is provided with a damper 34 whereby the 25 amount of fresh air entering the space within the furnace jacket 16 may be controlled or altogether checked.

In use the improved furnace will be placed in a furnace room F—R and the grating 25 30 will be positioned in the floor F of a room R above the furnace room. The grating 32, however, will be disposed in the floor F' of a room R', the latter room being preferably though not necessarily a lower hall. By this 35 arrangement, hot air will be discharged from the furnace into the room R and simultaneously with this operation, cool air will be drawn from said room and from the room R' to be reheated, it being understood that 40 the two rooms are in communication through means of transoms, doorways or other means. This affords a better circulation of air and consequently more efficient ventilation, and at any time fresh air may be admitted 45 into the system by operation of the damper 34, which latter may well be so constructed as to allow it to be actuated from the first floor of the building.

A water pan 35 is located within the shell 50 16 in order to supply the proper amount of moisture to the hot air expelled from the furnace, water being supplied to said pan through a pipe 36 which leads from a second pan 37 on the exterior of the furnace, 55 said pan 37 being preferably supported by a bracket 38 extending from said furnace as shown. A reservoir or supply tank 39 rises within the pan 37 and is provided with a valved water inlet pipe 40 which may be 60 used in buildings having running water therein, said tank however, being also equipped with a screw cap or the like 41 whereby it may be filled by hand. The lower

end of the tank 39 has one or more outlets 42 delivering into the pan 37, whereby as 65 long as the water level in said pan is above said outlets, air cannot enter the upper end of the tank and consequently, no more water can be discharged into the pan. However, when the water level in the latter lowers, due 70 to evaporation in the pan 35, the outlets 42 will be exposed with the result that air will enter the tank 39 through said outlets and will thus allow water to be discharged to again raise the level in the pan 37 to its normal position. Thus, an adequate amount of water will be supplied to the pan 35 at all times with the result that sufficient moisture will prevail in the heated air discharged from the furnace. 80

The tank 39 may have any desired capacity but it will preferably contain anywhere from ten to thirty gallons in order that the supply of water therein need not be often replenished. 85

In Fig. 2, the upper end of the shell 16 is shown as provided with a collar 50 from which a heat conducting pipe 51 may lead to any part of a building, said pipe preferably having a damper 52. 90

From the foregoing, taken in connection with the accompanying drawings, the construction, manner of operation and advantages of my improvements will be readily understood without requiring a more extended explanation. In conclusion, however, I wish it understood that although certain specific details of construction have been shown and described for accomplishing probably the best results, numerous changes may 100 be made within the scope of the invention as claimed. 95

I claim:

The combination of a heater, a cylindrical vertically disposed shell surrounding and 105 spaced from the same, a sheet metal top for said shell having a single central opening, a short heat discharge pipe rising from said opening, a grating extending over and horizontally beyond the upper end of said pipe, 110 and a unitary polysided wall surrounding said pipe and spaced therefrom, said wall extending the entire distance between said grating and the top of the shell, the corners of said wall resting on the edge of said top 115 over the curved wall of the shell and the lower edge of said wall having integral outstanding flanges secured rigidly to said top to prevent sagging thereof.

In testimony whereof I have hereunto set 120 my hand in presence of two subscribing witnesses.

JOHN THOMAS COLLINS.
